UNITED STATES PATENT OFFICE

NILS P. LILJEHOLM, OF ST. LOUIS, MISSOURI, ASSIGNOR OF ONE-THIRD TO
HENRY GOETZ, OF SAME PLACE.

RAILWAY-FREIGHT-CAR DOOR.

SPECIFICATION forming part of Letters Patent No. 293,479, dated February 12, 1884.

Application filed November 7, 1883. (No model.)

To all whom it may concern:

Be it known that I, NILS P. LILJEHOLM, of the city of St. Louis, in the State of Missouri, have invented a certain new and useful Improvement in Railway-Freight-Car Doors, of which the following is a full, clear, and exact description, reference being had to the accompanying drawings, forming part of this specification.

10 This invention relates to a combined grain-door and outer door.

Reference is made to the claims for statement of invention.

Figure 1 is an outside view of the door when closed. Fig. 2 is a transverse section at 2, Fig. 1. Fig. 3 is a front view of the door when open. Fig. 4 is an enlarged detail section at 4, Fig. 1.

15 A and B are side timbers of a freight-car. C is the floor, D the side walls, and E the door-posts. The door consists of an under part, F, and an upper part, G, fitted together at their meeting edges by a bevel-joint, H. The lower part, F, is supported at the upper portion by trunnions I, which rest in open-topped notches 20 or slots j in metal side pieces, J, which are secured to the side posts, E. The side pieces are set back from the corners of the posts, as shown, so as to form a rabbet-bearing for the edge of 25 the part F, which fits closely against the pieces J and the posts E, so that no grain can leak 30 through when the car is loaded with grain in bulk.

K is a metal strip or cleat overlapping the 35 lower edge of the lower parts, said edge entering the groove thus formed between the cleat and the floor of the car. The upper edge of the lower part is beveled at F', and upon this beveled edge fits snugly the lower (beveled) edge 40 of the upper part, G, so that the upper part holds the lower part down in place. I prefer to bind and thus protect the upper edge of the lower part or member, F, of the door with a bar, F', of iron, whose ends project and form 45 the round trunnions I. The part of the bar F' forming the top of the member is made flat to fit the lower edge of the upper member, G. The bar F' is held in place by straps F'', which are sunk into it on top and extend down upon 50 the outside and inside. The upper part or member, G, is suspended upon hangers L that slide

on a rod, M, that is secured to the side of the car beneath the eaves. The part G can be moved from the closed position shown in Fig. 1 to the open position shown in Fig. 3 without 55 moving the lower member or part, F, owing to the manner of connecting them.

N is a bar whose ends are secured to the upper part, G, and which stands out from the upper part, so as to allow the free passage 60 along it of the upper link of a chain, O, whose other end is attached to the lower part, F. The means of attachment allows the upper part to be opened or closed when the lower part is shut, and allows the lower part to be opened 65 or closed when the upper part is open; but neither of the parts of the door can be separated from the car. The lower part, when open, may be supported by the two trunnions I, resting at one end in a slot, j, and at the other in 70 a hook, P, secured to the side of the car. The lower edge of the lower part is held by a cleat, P', to prevent it swinging outward. The parts are locked together by a hasp, Q, fixed rigidly to upper part, G, and staple R on the lower part, 75 F, and any suitable lock. The upper part is in like manner secured to the side of the car by means of fixed hasps S and staples T, to receive locks, as usual.

To open the door, the upper part, G, is unfastened from the side posts and lower part and slid in inclined position to one side on the rod M, the bar N sliding in the upper link of the chain connected to the lower part, F. This leaves the lower part free to be lifted away 80 from the door opening out of the groove between the strip K and the floor to one side, the upper link of the connecting-chain sliding along the bar N until the lower part is hung on a side piece, J, and hook P. 85

To replace the door, the lower part is first lifted off its supports, the chain sliding to one side with it on the bar, and then dropped into the groove, its trunnions resting in the openings j. The upper part is next inclined on its 90 supporting-rod, so as to pass the upper end of the side piece and staples in the way, and slid to normal position over the lower part, the bar N sliding in the upper link of the chain. 95

I claim as my invention—

1. A freight-car door consisting of two parts, an upper and lower, the upper part secured to

the car, and the lower part connected to the upper part by a bar and chain.

2. The combination of a car-body having a door-opening, side pieces having slots at top 5 and a strip at bottom to form a groove, a door in two parts, an upper and lower, the lower part having trunnions to occupy the slots, and the upper part supported over the lower part, and the lower part supported in the groove and 10 between the side pieces by the trunnions.

3. The combination, with the lower part having trunnions, and a side piece having a slot at its upper end, of the hook to support the lower part away from the door-opening.

15 4. A freight-car door composed of a lower

member, F, secured in place by the cleat K, side strips or pieces, J, with open slots j and trunnions I, and the upper member, G, secured to the side of the car and bearing on the top of the lower member, F, for the purpose set forth. 20

5. The combination, in a freight-car door, of a lower member, F, supported in position by trunnions I, side pieces, J, and cleat K, and an upper member bearing on the lower member, and supported on hangers L and rod M, 25 substantially as set forth.

NILS P. LILJEHOLM.
